ELECTRICAL SWITCH

John A. Alexander, Pacific Palisades, Calif.

Application July 31, 1948, Serial No. 41,739

14 Claims. (Cl. 200—153)

1

This invention has to do with electrical switches or circuit controllers, and has as an object the provision of a switch which is highly economical of manufacture.

Another object is to provide a switch which is positive in action and provides an ideal type of contact.

A further object is to provide a novel switch mechanism which is readily adaptable not only to wall switches and the like but also to relays or multiple pole, multiple throw controllers.

Another object is to provide a switch which has effective safety provisions.

Still further objects and accomplishments of my invention will become apparent from the following detailed description of specific embodiments thereof, for which purpose I shall now refer to the accompanying drawings, wherein:

Fig. 1 is a side elevation, of which is shown a portion in section, of one form of switch embodying the invention, shown in open position;

Fig. 2 is a view similar to Fig. 1 but showing the parts in the first stage of a circuit closing operation;

Fig. 3 is a view similar to Figs. 1 and 2, showing the switch in closed position;

Fig. 4 is a view similar to Figs. 1, 2 and 3, showing the parts in the position which they occupy during the first stage of the operation to open the switch;

Fig. 5 is a top plan view;

Figs. 6 and 7 are enlarged cross sections on lines 6—6 and 7—7 of Figs. 1 and 3, respectively.

Fig. 8 is a side elevation, a portion being shown in section, of a modified form of the invention, showing an embodiment as a double pole, double throw switch;

Fig. 9 is a front elevation of the device shown in Fig. 8;

Fig. 10 is a bottom plan view of the same device, 40 and;

Fig. 11 is a fragmentary detail showing another modification.

Referring first to the embodiment of Figs. 1—7, the numeral 5 generally indicates a body consisting of a base 5a carrying end uprights 6 and 7, the base and uprights being shown as made of a suitable non-conductive material, such as a suitable plastic. If desired, the body may be mounted in a housing not shown.

A transverse opening 9 is provided through upright 6 to slidably carry an actuating plunger 10 which is loaded by a spring 15 acting between the upright 6 and a push button 16 on the outer end of the plunger. A collar 17 is fixed on the plunger

2

at the opposite side of the upright to limit movement of the plunger outwardly or to the right under influence of the spring. The plunger has a reduced diameter left-hand or inner end portion 18 providing an annular shoulder 19 at its point of intersection with the contiguous portion of the plunger, for the purpose to be described.

A pair of resilient arms 20, 21 are each rigidly secured to the upright 7 by means of bolts and nut units 23, 24, the latter of which provides a terminal to which one wire (not shown) of an electrical circuit is adapted to be connected.

A third resilient arm 25 is secured to the base by means of bolt and screw unit 26, which later 15 serves as a terminal for the other leg of the circuit.

I prefer to make the arms 20, 21, 25 of ordinary leaf springs and only one end of each is anchored.

20 Retaining arm 20 is provided between its ends with an opening 27 to receive the reduced upper end 25a of arm 25, the right hand end of the opening serving as an abutment for the end 25a to lock the switch in closed position (Fig. 3). The 25 outer or free end of arm 21 is upwardly curved for efficient contact with arm 25 in circuit closing position; and the outer or free end of arm 20 is diagonally downwardly disposed to facilitate its engagement with the shoulder 19 to effect opening of the switch for disengagement of the reduced end 25a with the abutment.

To limit downward swinging movement of arm 21 I provide a post 28 having a diagonal upper face 29. The post 28 also serves as a stop to limit flexure in one direction of arm 25.

The spring arm 20 is prestressed to cause it to bear downwardly against the free end of arm 25; arm 21 is prestressed to cause it to bear against the post 28 and arm 25 is prestressed to cause it to pull away from the free end of arm 21, as well as to snap out of the opening 27 during the switch opening movement, all as best appears in Fig. 1. The outer end portions of arms 21 and 25 may be considered as contact elements, and the prestressed inner end portions adjacent the base 5 may be considered as means for biasing the contact elements to their above described normal positions.

50 In operation, commencing with the parts in the open position of Fig. 1, to close the switch the plunger 10 is pushed inwardly to the position of Fig. 2, causing arm 25 to engage the curved end of arm 21 with a rubbing action so desirable to ideal contact, and permitting the reduced end 25a of arm 25 to snap into the

opening 27. Upon release of the plunger the spring 15 returns it to the position of Figs. 1 and 3, the collar 17 acting as a stop against further outward movement of the plunger, and the free end of arm 20 snaps into the position of Fig. 3, in the path of shoulder 19 for the next subsequent operation. Inasmuch as the end 25a of arm 25 is engaged in the opening 27, the switch is held in that closed position until the plunger is again operated to open the switch.

To open the switch from the position of Fig. 3, the plunger is again pushed inwardly, the shoulder 19 engaging the free end of arm 20 and bowing the arm upwardly until the reduced end 25a of the arm 25 is released from engagement in the opening 27, which takes place automatically since the arm 25 is resilient and is stressed to flex to the right to the position of Fig. 1. Release of the plunger then permits the parts to return to the position of Fig. 1.

In Figs. 8 and 9 and 10, I show an adaptation of my invention as a double pole, double throw switch.

Here the L-shaped base or body 30 has secured to its lower end 30a a bifurcated insulating pad 31, the pad being secured as by screws 32. The lower end 30a presents a slot 34 in which a contact plate or actuating arm 35 is pivoted to swing, the plate having cutaway portions 36 to fit in the slot.

A coil or electro-magnet 40 has its core 41 secured to the upright portion of the body as by a screw 42, the outer end of the core being disposed for contact with the swingable plate 35 when the electro-magnet is energized through wires W, W'. Secured to one of the branches 31a of the bifurcated pad 31, as by screws 37, with insulating strips 38 between and on each side of them, there are three resilient contact arms 45, 46, 47. Like arms 45a, 46a, 47a are secured to the other branch 31b of the pad 31 as by screws 49. The medial arms 47, 47a have secured to their free ends a cross bar 50 of insulating material, the cross bar having a medial upstanding finger 51 for the purpose to be described.

A pair of contact elements 52, 53 are secured, one on each side of arm 47 adjacent the upper end thereof, and a like pair of contact elements are secured on arm 47a.

Each of the arms 45, 46 has a contact element 56, 57 respectively, secured on its free end for alternate engagement with the contact elements 52, 53 in response to movement of the arms 47, 47a.

To normally urge the plate 35 away from the core 41, I provide a coil spring 60, one end of which is secured to the lower end of the plate and the other end of which is secured to a depending bracket 61 mounted on the base portion 30a. Thus the outer end portion of the slot 34 in the body portion acts as a fulcrum for the plate 35.

Plate 35 carries an arm 63 extending upwardly therefrom with its top end disposed for engagement with the cross bar 50 when the coil is energized. Arm 63 has a lateral projection 65 presenting an upwardly opening notch 66. A downwardly curved leaf spring 67 is secured at one end to the upright portion of the body by a screw 68 and is stressed to bear toward the cross bar 50. The spring arm 67 has a hole 69 into which the finger 51 on the cross arm enters in one position of the switch. The outer end of arm 67 bears towards the projection 65 and its free end is disposed to enter the notch 66 in one position.

The device described, being of the double pole, double throw variety, is adapted to control four circuits—that is, leads are attached to each of the arms 45, 46 and a common return lead is attached to the pole arm 47 while leads are also attached to each of the arms 45a, 46a, and a common return lead is attached to the pole arm 47a.

Operation of the device is as follows: In the position of Fig. 8 the electro-magnet is de-energized, permitting the spring 60 to swing the plate 35 to the right. The medial arms 47, 47a are prestressed to bear to the right so that contacts 53 engage the contacts 57, thus closing two of the circuits. The switch elements are maintained in that position not only by the resiliency of the arms 47, 47a, but also by the spring 67 bearing downwardly against the finger 51 to frictionally oppose movement thereof. To open the last mentioned circuits and to close the other circuits through arms 45, 45a, 47, 47a, the electro-magnet is energized momentarily to draw the plate 35 against the core and to cause the free end of arm 63 to engage and move the cross bar 50 and thus to swing arms 47, 47a to the left to cause the contacts 52 to engage the contacts 56, and to cause the contacts 53 to disengage from contacts 57. The parts are held in this position by the finger 51 engaging in the hole 69 of the spring arm 67. Then, to open the latter circuits and to return the parts to the position of Fig. 8, closing the first mentioned circuits, the coil is again momentarily energized, drawing the plate 35 and its carried arm 63 towards the core. This movement of arm 63 causes the notch 66 in the projection 65 to engage the free end of spring arm 67 and bow said arm upwardly sufficiently to free the finger 51 from the hole. The electro-magnet being then de-energized, the arms 47, 47a swing to the right by virtue of their own resiliency to cause the contacts 53 again to engage the contacts 57.

It will be observed that at no time is it necessary to hold the electro-magnet energized since a momentary energization causes full actuation of the switch elements.

In Fig. 11, I show a modification wherein the parts are as before described and are given like reference numerals, excepting only that here I provide a stop or abutment to limit the extent to which the leaf spring arm 67 may be bowed outwardly in the course of its flexure by the arm 65. Here I secure to the upright portion of the body 30, as by a screw 70, a plate 71 to which I fix an insulating pad 72 in position to be engaged by the spring 67 after limited upward bowing movement.

While I have described three specific adaptations of my invention in rather minute detail, I wish it understood that within the broader scope of the invention as defined by the appended claims, other embodiments, which will become apparent to those skilled in the art from a reading of the foregoing explanation, are possible.

65 I claim:

1. In an electrical switch: a body; a pair of contact elements carried by said body, at least one of which is movable relative to the other alternatively into two positions, one of which is a position of contact of the two elements with each other and one of which is an open position; biasing means holding the movable contact element in a first one of said two positions; a spring arm carried by the body, said arm carrying an abutment catch engageable with the movable

contact element when in a second one of said two positions to releasably hold it in said second position against the action of said biasing means, the spring arm being permanently spring biased to be urged toward the position in which said catch is held in engagement with said movable contact element; a resiliently automatically retractable movable member mounted on the body, and disposed to be moved from its retracted position a first time in one direction to move the said movable contact element into said second position in which said movable contact element is engaged and held by said catch, said movable member being thereafter automatically retractable in the opposite direction away from the held movable contact element; and means movable in each direction with said retractable movable member, the path of movement of said means in its movement in said one direction being such that it engages and flexes said spring arm away from said position of engagement of said catch with said movable contact element, when the spring arm is in said engagement position, and the path of movement of said means in said one direction being such that it also fails to thus engage and flex said spring arm, when said spring arm is not in said engagement position, whereby upon a second movement of said resiliently retractable member in said one direction, said movable contact element is disengaged from said catch and is free to return to its first position under the action of its biasing means.

2. The combination defined in claim 1, in which said spring arm is a leaf spring secured at one end to the body with its outer portion overlying the movable element, the abutment catch being provided on the spring arm between its ends, and in which said means movable with the retractable member engages the outer end of the spring for said flexing action.

3. The combination defined in claim 2 in which the catch abutment is the end wall of a longitudinally extending slot in the leaf spring arm, and the outer end of the movable contact element is shaped with a tongue to enter said slot.

4. The combination defined in claim 1, in which the resiliently retractable movable member is the armature of an electromagnet, and in addition thereto an electromagnet for said armature.

5. In an electrical switch, a body carrying a first contact element and a resilient second contact element comprising a spring arm anchored to the body at one end only, flexible to bring its movable end into contact with said first contact element and prestressed to normally move its movable end away from the first contact element, a retaining arm resiliently swingable to bear constantly against the outer end portion of said second contact element, said end portion being contactually slidable lengthwise of the retaining arm as the second contact element moves relatively to the first contact element, said arm having an abutment engageable by the outer end portion of said second contact element as it slides along the retaining arm to catch and retain the second contact element in contact position, and means carried by the body for movement into position flexing said arm sufficiently to free said second contact element from engagement with said abutment.

6. In an electrical switch, a body carrying a contact element, a resilient contact arm secured at its inner end to the body and disposed for engagement at its outer end portion with the contact element, said arm being stressed to bear

away from engagement with said contact element, a leaf spring secured at its inner end to the body and overlying and stressed to bear against the outer end of said arm, said arm having an outer end projection and said leaf spring presenting a transverse hole adjacent said projection positioned to receive said projection when the contact arm is in engagement with the contact element, a plunger slidably mounted in the body, the plunger being engageable during a first movement of the plunger with said contact arm to move the latter into engagement with the contact element, and an abutment on the plunger positioned to engage the outer end of the leaf spring when the projection is engaged in said hole whereby a second movement of the plunger functions to engage said abutment with the outer end of the leaf spring and to flex the latter sufficiently to disengage the projection from the hole.

20 7. In an electrical switch, a body carrying a contact element, a resilient contact arm secured at its inner end to the body and disposed for engagement at its outer end portion with the contact element, said arm being bowed toward and stressed to bear away from engagement with said contact element, a leaf spring secured at its inner end to the body and overlying and stressed to bear against the outer end of said arm, said arm having an outer end projection and said leaf spring presenting a transverse hole adjacent said projection positioned to receive said projection when the contact arm is in engagement with the contact element, a plunger slidably mounted in the body, the plunger being engageable during a first movement of the plunger with said contact arm to move the latter into engagement with the contact element, and an abutment on the plunger positioned to engage the outer end of the leaf spring when the projection is engaged in said hole whereby a second movement of the plunger functions to engage said abutment with the outer end of the leaf spring and to flex the latter sufficiently to disengage the projection from the hole.

35 8. In an electrical switch, a body carrying a contact element, a resilient contact arm secured at its inner end to the body and disposed for engagement at its outer end portion with the contact element, said arm being stressed to bear away from engagement with said contact element, a leaf spring secured at its inner end to the body and overlying and stressed to bear against the outer end of said arm, said arm having an outer end projection and said leaf spring presenting a transverse hole adjacent said projection positioned to receive said projection when the contact arm is in engagement with the contact element, a plunger slidably mounted in the body, the plunger having a reduced diameter outer end portion engageable during a first movement of the plunger with said contact arm to move the latter into engagement with the contact element, said reduced diameter outer end portion providing an annular shoulder at its point of intersection with the larger diameter portion of the plunger which said shoulder is positioned to engage the outer end of the leaf spring upon a second movement of the plunger and to flex the leaf spring sufficiently to disengage the projection from the hole.

65 9. In an electrical switch, a U-shaped body having secured to one of its sides a flat spring contact, and a leaf spring retainer having an opening between its ends and overlying said contact, a leaf spring contact secured at one end

to the bottom portion of the body, the leaf spring contact being bowed towards the flat spring contact, having an end projection terminating in engagement with said retainer and being stressed normally to bear away from the flat spring contact, and a plunger slidably mounted in the other side of the body having two transversely arranged faces, one for engagement with the leaf spring contact and one for engagement with the outer end of the retainer.

10. In an electrical switch having a movable resilient contact presenting a projection, and a plunger having two transversely arranged faces, a first one of said faces operatively engaging said contact, a retainer for releasably holding said contact in a circuit closing position, said retainer comprising a leaf spring anchored at one end and having its free end disposed to be engaged by the second of said plunger faces, said spring having between its ends a hole to receive said projection of the resilient contact.

11. In an electrical switch, a body, a pair of resilient contact arms carried by the body, the first of which is flexible into engagement with the other, actuating means for flexing said first arm into rubbing engagement with the other to close a circuit, and a leaf spring secured at one end to the body, said spring having an abutment engageable with said first arm to hold it in circuit closing position, said actuating means being disposed for engagement with said spring to flex it sufficiently to release the first arm from the abutment.

12. An electrical circuit controller comprising an electro-magnet carried by the body, an actuating arm hingedly carried by the body for swinging movement in one direction in response to the electro-magnet, spring means urging the arm in the opposite direction, said arm presenting a notch, a leaf spring fixed at one end to the body and normally bearing at its other end toward but spaced from said arm adjacent the notch, said leaf spring having a transverse opening therein, two sets of relatively movable contact elements mounted on the body at opposite sides of the leaf spring, and a cross arm of non-conducting material carried by and extending from a movable contact element of one set to a correspondingly movable contact element of the other set in the path of movement of the actuating arm, said arm having a projection engageable in said opening in the leaf spring when said movable contact elements are moved into circuit closing position by movement of the actuating arm against said cross arm, and said leaf spring being flexible in response to movement of the actuating arm when the outer end of the leaf spring is engaged in said notch to disengage said projection from said hole, said engagement of the projection with the said opening permitting movement of the outer end of the leaf spring into contact with said actuating arm adjacent said notch and into engagement with said notch upon movement of said actuating arm.

13. An electrical circuit controller comprising a pair of spaced resilient electrically conductive

5 arms each of which is adapted for connection to a lead wire of an independent circuit, means anchoring said arms at one end only, a contact element carried by the free end portion of each of said arms, a third electrically conductive resilient arm disposed between the first mentioned arms and anchored at one end, said third arm being adapted for connection to a return lead wire common to both said independent circuits and having at its free end portion opposed contact elements positioned for alternate engagement with the first mentioned contact elements, the third arm being prestressed to be urged by its resiliency away from one of the first mentioned contact elements and into contact with the other of said first mentioned contact elements, actuating means for moving the third contact arm in the opposite direction, retaining means for releasably holding the third arm at the end of the last named movement, and means controlled by and operable with said actuating means for releasing said retaining means.

14. An electrical circuit controller comprising a pair of spaced resilient electrically conductive arms each of which is adapted for connection to a lead wire of an independent circuit, means anchoring said arms at one end only, a contact element carried by the free end portion of each of said arms, a third electrically conductive resilient arm disposed between the first mentioned arms and anchored at one end, said third arm being adapted for connection to a return lead wire common to both said independent circuits and having at its free end portion opposed contact elements positioned for alternate engagement with the first mentioned contact elements, the third arm being prestressed to be urged by its resiliency away from one of the first mentioned contact elements and into contact with the other of said first mentioned contact elements, actuating means for moving the third contact arm in the opposite direction, retaining means independent of its electrical contact surface for contactually engaging and releasably holding the third arm at the end of the last named movement, and means responsive to an independent movement of the actuating means in the last named direction, to release said retaining means.
